UNITED STATES PATENT OFFICE.

JOHN H. JACOBSEN, OF WORCESTER, MASSACHUSETTS, ASSIGNEE TO CROMPTON & KNOWLES LOOM WORKS, OF WORCESTER, MASSACHUSETTS, A CORPORATION OF MASSACHUSETTS.

LIFTER ROD FOR LOOM DOBBIES.

Application filed November 6, 1924. Serial No. 748,255.

This invention relates to improvements in loom dobbies and more particularly to the lifter rods which are employed for raising the upper set of hooks and the method for making the same.

In mechanisms of this type there are employed oppositely reciprocating knives which cooperate with hooks operatively connected in pairs to the harness lifting levers. The position of the hooks with respect to the knives is controlled by a pattern mechanism under the lower set of hooks and the indication from the pattern surface is carried to the upper set of hooks by means of lifter rods. These rods are guided so as to be held in place and are preferably formed with a broadened upper surface. There is likely to be relative motion between the hook and the broadened surface such as will wear a groove in the latter and it is the principal object of my invention to form the rod in such a way as will provide a broad bearing surface which will also act as a guide and which will further be provided with an upper surface of hardened steel.

My invention further relates to the method of making the rod wherein the steps of the process leave a finished article ready for use without further machining.

With these and other objects in view which will appear as the description proceeds, my invention resides in the combination and arrangement of parts hereinafter described and set forth in the claims.

In the accompanying drawings wherein I have shown one form of rod and have illustrated one method of producing the same,

Fig. 1 is a front elevation of such portions of a loom dobby as will indicate the manner in which my improved rod is used.

Fig. 2 is a horizontal section on line 2—2 of Fig. 1 looking in the direction of the arrows, and

Figs. 3, 4, and 5 represent the successive steps followed in the process of forming my improved rod.

Referring more particularly to Figs. 1 and 2 it will be seen that I have provided the usual dobby frame 10 having oppositely reciprocating upper and lower knives 11 and 12, respectively, actuated by mechanism not shown and cooperating at selected times with

upper and lower hooks indicated respectively at 13 and 14. The said hooks are connected in pairs to levers 15, one of which is pivoted to each of the harness levers, one of which is indicated at 16.

The position of the hooks is determined by a set of indicators indicated at 17, each of said indicators having a pocket 18 and an upstanding finger 19 and being controlled as to vertical position by means of pattern mechanism indicated at 20. The finger 19 is positioned for engagement with the lower hooks and the pocket 18 receives the lower end of my improved rod 30 the upper end of which is formed according to my invention and is adapted to control the vertical position of the upper set of hooks. When the indicators 17 are down the hooks will be raised out of operative relationship with the knives. My invention relates more particularly to the formation of the head 31 on the rod 30.

In carrying out my invention I provide each rod with a head 31 having passing therethrough a bore or opening 32 which is preferably so proportioned as to hold the head frictionally on the upper end of the rod. The head is moved along the rod so that the end of the latter will project beyond the head as indicated in Fig. 4, after which electrodes 33 and 34 can be brought into position to soften the end of the rod and head the same over to form a smooth convex surface. The head 31 and wire are welded together but the head, being considerably larger in cross section than the wire, is not heated sufficiently to be deformed. The electrodes are then removed leaving the rod as indicated in Fig. 5 with an upper convex surface which when placed in the dobby will support the upper hooks.

I find it desirable to make the rod 30 of relatively hard material so that the wearing surface indicated at 35 will be able to withstand considerable wear. The head serves the double purpose of supporting the convex end of the rod 35 and of positioning the rod in the manner indicated in Fig. 2. The dobby is provided with a comb 21 between the dents of which the hooks 13 extend. The teeth of the comb are indicated at 22 as being spaced apart a distance slight-

ly less than the diameter of the head 31 and the bar 23 forming the lower portion of the comb and cast integral with the teeth prevents backward motion of the rod 30. 5 The head and rod are therefore positioned but are free to move vertically to position the hooks. Although the upper surface of the head 31 is shown as flat, yet I do not wish to be limited to this construction. 10 From the foregoing it will be seen that I have provided an improved lifter rod having a head of relatively large cross section formed of comparatively soft steel and having an upper surface formed by expanding 15 a comparatively hard rod so that the end of the latter is spread over the top of the head to present a wearing surface for the dobby hooks. Also, it will be seen that my improved method of manufacturing 20 these rods presents a convex shell of hard material spread over a comparatively soft head, the relative movement of the parts during the welding being prevented by the relatively close fitting between the rod and 25 the hole formed in the head. It is found that the rod heats more quickly than the head and the expansion due to the heating also serves to tighten the contact between the rod and the head. 30 Having thus described my invention it will be apparent that changes and modifications may be made therein by those skilled in the art without departing from the spirit and scope of the invention, and I do not

wish to be limited to the details herein disclosed, but what I claim is:

1. A lifter rod for loom dobbies having a body portion of comparatively hard material, and a head of softer material and larger cross section held to the rod, the rod having a portion thereof expanded and spread over the upper surface of the head to present a hard wearing surface. 35

2. A lifter rod for loom dobbies having a body portion of comparatively hard material and having a head held to the body portion, the rod extending through the head and being expanded to cover a portion of the latter to present a hard wearing surface. 45

3. A lifter rod for loom dobbies comprising a head of comparatively soft material and a wire of comparatively hard material extending through the head and having the upper portion thereof spread over the upper surface of the head to form a convex hardened bearing surface. 55

4. A lifter rod for loom dobbies formed of a wire of comparatively hard steel and a head of comparatively soft steel welded thereto, the wire extending entirely through the head and having a portion thereof expanded and spread over the upper surface of the head. 60

In testimony whereof I have hereunto affixed my signature.

JOHN T. JACOBSON.
